UNITED STATES PATENT OFFICE

HARRY M. PATERNAYAN, OF NEW YORK, N. Y.

LOOM

Application filed May 17, 1930. Serial No. 453,425.

This invention relates to looms.

It is among the objects of the present invention to provide a novel and improved automatically-operable knot-tying loom.

5 It is a further object of the present invention to provide a loom of improved construction adapted for the selective tying of variously colored knots on warp threads.

A further object of the present invention 10 is to provide a knot-tying loom particularly adapted for the formation of rugs or other pile fabrics, which is completely automatic in its operation for the tying of knots in a single row across the machine.

15 A further object of the present invention is to provide such a device incorporated with which there is provided means for predetermining and preselecting the color arrangement of the knots tied.

20 Generally speaking, the present invention includes a stationary loom base, across which upper and lower structures are moved in time-controlled manner by the general operating motor, the movement being periodically stopped to permit the tying of pile threads 25 on adjacent warp threads. Between the operation of the needles in taking thread from a bobbin and tying it on the warp thread, means are provided for selectively moving the series of bobbins to select the thread tied 30 by the needles, and after the tying of such thread, means are provided for moving the knot forwardly on the thread to push it into proper position with respect to the knots formerly tied. To accomplish these ends in an 35 automatic manner, various cam assemblies are provided and structural details to which the invention is not limited.

Other objects and features of the present 40 invention will be understood from a consideration of the following specification, taken in conjunction with the accompanying drawings, in which

45 Figure 1 is a plan view of one form of the present invention;

Fig. 2 is a vertical longitudinal section taken on the line 2—2 of Fig. 1;

Fig. 3 is a vertical cross section taken on the line 3—3 of Fig. 2;

Fig. 4 is a horizontal sectional view taken on the line 4—4 of Figs. 2 and 3;

Fig. 5 is a vertical section taken on the line 5—5 of Fig. 3;

Figs. 6, 7 and 8 are detail views showing the knot-moving mechanism;

Fig. 9 is a detail plan view of the knot-moving mechanism;

Fig. 10 is a detail sectional view taken on the line 10—10 of Fig. 5;

Fig. 11 is a detail view of the needle-operating cam;

Fig. 12 is a sectional view taken on the line 12—12 of Fig. 2;

Fig. 13 is a similar view, but showing the jaws closed;

Fig. 14 is a sectional view taken on the line 14—14 of Fig. 1;

Fig. 15 is a horizontal section taken on the line 15—15 of Fig. 2;

Fig. 16 is a sectional view taken on the line 16—16 of Fig. 1;

Figs. 17, 18 and 19 are elevational views of the needle assembly in various operating positions;

Fig. 20 is a side elevation showing the warp feeding mechanism;

Fig. 21 is a detail section taken on the line 21—21 of Fig. 2;

Fig. 22 is a view of the scissors operating cam;

Fig. 23 is a face view of one of the thread bobbins in association with the needles and warp;

Fig. 24 is a side view;

Figs. 25 to 32 are diagrammatic illustrations showing the various steps in the thread tying operations;

Figs. 33, 34, 35 and 36 are diagrammatic views showing the operation of the machine to form a Chinese knot on the warp;

Fig. 37 is a detail view of a modified form of needle.

By referring to the drawings, it will be seen that the device includes a stationary supporting structure 10, and an upper and a lower transversely movable structure 11 and 12, respectively. The movable structures 11 and 12 are united and are adapted to be simultaneously transversely moved by interconnected worm shafts 13 and 14, respectively. Across the stationary frame, warp threads 15 extend, being supplied from a warp beam 16 and a cooperating beam 17 adapted to receive a finished rug or fabric. The form of the invention here shown is powered by a suitable electrical motor 18 or its equivalent, a main drive shaft 19 being driven thereby, from which chains or other driving means extend to the various shafts of the device, as will be hereinafter described. Associated with the main frame, suitable heddles 20 are provided for guiding the warp threads 15.

The needle assembly of the present invention includes a pair of co-operating needles 21, the upper ends of which are recessed to provide thread-engaging hooks at the extremities of the needles. The modified form of the needle, as shown in Fig. 37, is provided with a downwardly-extending prong 21A, which serves to provide an improved grip of the thread by the needle. The needles 21 are united for respective pivotal movement by inwardly-extending apertured ears 22, the apertures of which receive therethrough a supporting and pivoting pin 23 mounted upon a transverse vertically-reciprocating shaft 24. The shaft 24 extends through vertical guide apertures 25 of the movable structure 12, one side of which is preferably provided with extended guide flanges 26 to insure proper alignment and guided movement of the shaft 24. Externally of the structure 12, the ends of the shaft 24 have mounted thereon depending links 27 which extend to operating wheels 28 mounted upon the extremities of a transverse shaft 29. Within the sides of the structure 12, the shaft 29 is provided with a gear 30, which enmeshes with a driving gear 31 slidable on and rotatable with a transverse drive shaft 32, one end of which is driven by a chain 33 from the shaft 19, the relative size of the gear connections being such that the shaft 29 is operated at twice the speed of the shaft 19, whereby the needles will move upwardly and downwardly twice during one revolution of the shaft 19. The lower extremities of the needles are provided therebetween with a camming wheel 34, the shaft 35 of which passes therethrough. The shaft 35 is supported by arms 37 extending from the shaft 24. The shaft 35 is journaled in the extremities of the arms 37 for rotary movement therein. One extremity of the shaft 35 is mounted within a guideway 36 associated with one of the side plates of the

structure 12. The guide way 36 is angularly disposed, the arrangement being such that its upper extremity is spaced from the straight vertical path of the shaft 24, so that when the shaft 24 is moved upwardly, the lower end of the needles is moved away from the shaft to tilt the upper end of the needles forwardly, the forward tilted position of the needles being indicated in Fig. 5. The arrangement is such as to provide for the needles a straight upward movement terminating at its upper extremity in an arcuate forward tilting path, from which they pass downwardly into the straight lower movement of their cycle. 80

For pivotally moving the needles, a spreader assembly, as will be hereinafter described, is provided, and in conjunction therewith the free end of the shaft 35 includes a disk 38 having extending fingers 39, while the structure 12 has a bifurcated arm 40, between the furcations of which a pivoted finger 41 is mounted, shown in detail in Fig. 11. The arrangement is such that downward movement of the shaft 35 will bring the fingers 39 in contact with the finger 41, whereby rotation will be imparted to the shaft 35. As by the construction the finger 41 is free to move upwardly, it will be seen that upward movement of the shaft 35 does not cause rotation of the shaft 35 or the cam wheel associated therewith. In the original upward movement of the needle assembly, the needles are parallel. Upon downward movement of the first cycle, the wheel is turned as indicated in Fig. 19 to bring the ends of the needles together. They are retained in this position by the cam wheel until the end of the second cycle, at which time the wheel is again rotated by contact of the fingers 41, to permit the needles to assume the normal parallel relation as shown in Fig. 17. 95

For selectively holding a plurality of short lengths of variously colored threads for engagement by the needles during the forward movement in the arcuate path of their first cycle, a bobbin assembly is mounted over the warps in the upper transversely movable structure 11. The bobbin assembly, as shown more clearly in Figs. 2 and 5, includes a plurality of bobbin disks 42, each of which has an angular collar 43 mounted upon a similar angular sleeve 44. The disks 42 include a plurality of pairs of bifurcated thread-holding fingers 45. The bobbins are encased within a housing 46, the rear extremity of which extends over an extension of the sleeve 44. The housing 46 and the bobbins therein are slidably mounted on the sleeve 44, the assembly being longitudinally movable in response to pivotal movement of a cam-operated lever 47, as will be hereinafter described. 110

For selectively moving the bobbin assembly in accordance with a predetermined design, the rear end of the sleeve 44 is provided 125

with a plurality of recesses 48, within which selectively operated pivoted jaws 49 may be received, a pair of jaws being provided for each of the recesses 48. By referring more particularly to Figs. 12 and 13, it will be seen that each jaw 49 is supported by supporting arms 50, rigidly associated with the upper structure 11, and that the jaws are substantially bell-crank shaped in configuration, their lower extremities being recessed within the recesses 48 while the opposite ends of the crank are toggly joined with a depending link 51 of a rocker arm 52. The rocker arm 52 is centrally supported, as at 53, from the structure 11, its opposite end being associated with links 54, the upper end of which is joined to the intermediate portion of one of a plurality of levers 55. The forward ends of the levers 55 are pivotally joined with the vertical portion of the structure 11, while the rear extremities are provided with depending fingers 56, which normally rest upon a fixed pattern plate 57 supported on an apertured stationary table 58 of the stationary structure 10. This arrangement is such that as the upper structure 11 moves transversely of the device, the registration of one of the fingers 56 within one of the apertures of the plate 57, permits the lever 55 to drop downwardly, thus dropping the link 54, pivotally moving the rocker arm 52, and raising the link 51 to close the jaws 49 within their particular recesses, the closed position of the jaws being shown in Fig. 13.

For raising all of the levers 55 to disengage any of the fingers 56 from the apertures of the plate 57, thus to permit transverse movement of the structure 11 over the device, a pusher bar 59 is provided, which extends vertically at the rear end of the machine, its lower end having a wheel 60 in contact with a cam 61. The shaft 62 of the cam 61 is driven by the main shaft 19 through a chain drive 63 at one-half the speed of revolution of the shaft 29. The arrangement is thus seen to be such that during each two cycles of the needles, the pusher bar 59 moves up at once to hold the fingers 56 out of engagement with the plate 57, so, as to permit transverse movement of the structure 11. The position of the cam 61 on its shaft 62 is such that the needles when in the position at the end of their two cycles are downward, whereby the movement of the upper and lower structure will not interfere therewith.

Driven by the chain 64 from the shaft 62, a cam shaft 65 is provided, the cam 66 of which is in contact with a roller 67 at the upper end of the lever 47. The position of the cam 66 with respect to the cam 61, is such that the lower end of the lever 47 urges the bottom assembly forward when the levers 55 are raised by the pusher bar 59. When the pusher bar moves downward, the registration of one of the apertures of the plate 57 with one

of the fingers 56, permits that finger to move further down, thus closing the jaws associated therewith. At the same time, the cam 66 rotates to permit the forward movement of the upper end of the lever 47 under the influence of its associated spring 68. The forward movement of the upper end of the lever 47 moves rearwardly its lower end, thus moving rearwardly the bobbin assembly. The rearward movement of the bobbin assembly is, however, stopped by the jaws 49 received within their recess. If the forward jaw 49, as shown in Fig. 2, is closed by the downward movement of its lever 55, no movement of the bobbin assembly will take place. If, however, one of the other of the levers were lowered by registration of its finger with one of the apertures of the plate 57, then the bobbin assembly would be free to move back until the striking of the rear extremity of the housing 46 with the jaws 49. This movement would bring a different one of the bobbin disks into alignment for engagement of the threads carried thereby with the needles. This arrangement is seen to be such that the apertures of the plate 57 provide a selection of the thread moved by the needles. Thus by providing variously colored threads on the bobbin disks, various designs may be automatically provided by configuration of the plate 57.

For rotating the bobbin plate from which thread has been taken in prior movement of the needles, the sleeve 44 is provided with an inner rotatable and longitudinally fixed shaft 69. Intermediate the ends of the shaft 69, a fixed angularly faced nut 70 is mounted, secured for rotation therewith by a pin 71. The nut 70 forms a continuation between the forward and rearward ends of the sleeve, but is rotatable with respect thereto by rotation of the shaft 69. Its position is such that it engages for rotation therewith the angular inner faces of the aperture of the collar of the bobbin disk from which thread has been taken by the needle. Thus as the bobbins move over the sleeve 44, the operating one thereof will be engaged by the nut 70 and upon rotation of the shaft 69, the bobbin will be rotated.

For rotating the shaft 69, its forward end is provided with a sprocket wheel 72, having a plurality of extending fingers 73. Associated therewith a transverse shaft 74 is provided, driven by a chain 75 at a speed equal to the speed of the shafts 62 and 65. Slidably mounted on the shaft 74 for rotation therewith, a sleeve 76 having an extending finger 77 is mounted. The sleeve is mounted for sliding movement on the shaft 74, with transverse movement of the upper structure 11, by end collars 78 mounted on the upper structure. The arrangement is such that upon rotation of the shaft 74, the finger 77 will strike one of the fingers 73 of the

sprocket wheel 72, to give the shaft 69 a partial rotation whereby the next adjacent pair of fingers of the rotated bobbin disk will straddle the arcuate upper path of the needles so as to provide thereacross a thread to be received thereby. The position of the finger 77 is such that the rotation of the bobbin is just after the completion of the rearward movement, if any, of the bobbin assemblies, so that rotation is given to that bobbin from which thread is to be taken by the needles.

By referring more particularly to Fig. 1, it will be seen that the device has a plurality of warp threads 15 extending thereacross. The upper and lower structures are thus designed to move simultaneously across the device so that the needles act to tie knots of thread taken from the bobbin over adjacent warp threads to form a transverse row of knots across the warp threads, the warp being then moved and the upper and lower structures reset to again tie a series of knots across the warp threads. For transversely moving the upper and lower structures simultaneously, the threaded upper and lower shafts 13 and 14, respectively, are provided.

By referring to Fig. 14, it will be seen that the rotation of the threaded shafts is provided for by a cam 79, which is mounted on the end of a shaft 80 driven by a chain 81 from the shaft 74, at a speed of rotation equal thereto. The cam 79 vertically reciprocates a shaft 82, which is provided with upper and lower links 83 and 84, respectively. Each of the links is provided with pawls which engage the ratchet teeth of ratchet wheels 85 and 86, rotatably mounted, respectively, upon the shafts 13 and 14. Mounted upon the upper and lower structure, spring-urged blocks 87 are mounted, the blocks having threaded surfaces engageable with the threaded surfaces of the shafts, as seen in detail in Figs. 14 and 16. The arrangement is such that when the blocks 87 engage the threaded surfaces of the shafts, they are moved transversely thereof by a worm drive to cause simultaneous transverse movement of the upper and lower structures. When it is desired to speedily move the upper and lower structures, for instance, at the completion of the formation of one row of knots, the hand lever 88 is moved which rotates with it a toothed gear 89, on either side of which are segmental gears 90 engageable therewith. The segmental gears 90 which are partially rotated by movement of the handle 88 have associated therewith, fingers 91 which engage buttons 92 on the shaft 93 of the block 87, thus moving the block away from the threaded shaft 60 against the tension of the spring 94, whereby the upper and lower structures are released from the threaded shafts and may be moved manually. The configuration of the cam 79 is such that the threaded shafts are rotated just as the needles are starting upward on

their first cycle and before any of the other cams have operated. Thus the structures are moved prior to the longitudinal movement of the bobbins on their rotation and prior to the movement of the needle spreader and knot jaws, which will be hereinafter described.

By referring to Figs. 23 to 29, inclusive, of the drawings, it will be seen that the needles first move upwardly on either side of one pair of warp threads. After the heads of the needles are passed above the warp threads, it is desirable to spread the heads apart to provide for their securing of a thread from the bobbin in position thereover. The intermediate pivotal connection of the needles provides for such movement and, as indicated in Figs. 17 and 18, it will be seen that the cam wheel is in the initial movement of the needles in proper position to permit such spreading.

A needle spreader and knot-moving assembly is provided, as shown more clearly in Figs. 5 to 9, inclusive, and 15. As shown in Fig. 15, the assembly includes a rigid yoke 95, including a rearwardly extending shaft 96, to the rear end of which is attached a spring 97, which normally urges the whole assembly forwardly. The movement of the assembly is controlled by a rocker arm 98 mounted upon a shaft 99, the upper end of the rocker arm 98 being provided with a roller 100, which bears against the face of a cam 101. The cam 101 is rotated by a chain 102 driven from the shaft 65 and at a speed equal thereto. The configuration of the cam is such that the lower end of the rocker arm 98 is forced rearwardly holding the spreader assembly out of action until the needles are in fully raised position. The cam has by this time rotated one-fourth of a revolution, which permits the assembly to move forward just enough to have the spreader finger 103 in position to cam apart the upper ends of the needles after they have passed between the warp threads, such position being indicated in Fig. 18. As the needles move downwardly, the cam 101 is rotated to move the spreader again rearwardly a short distance, so that upon the next upward movement of the needles, the upper ends will be forced by the cam wheel 34, as hereinbefore described, and the needles will pass between the two warp threads which were previously between the two needles. This upward movement of the needles is indicated in Figs. 29, 30 and 31. The conformation of the cam 101 is such that toward the end of the second cycle, of the needles, the lower end of the rocker arm 98 is allowed to move forwardly under the influence of the spring 97, and in such movement the upper ends of the knot are secured by a spring finger 104 of a pair of pivoted pusher jaws 105. The jaws 105 are pivotally mounted upon a forward extension 106 of the

shaft 96, and are urged together by a spring 107.

In the previous movements of this assembly, the ends of the jaws have been forward 5 of the knot. As the spreader is withdrawn 10 the jaws are brought back past the knot and forward movement thereof brings the jaws into engagement with the ends of the knot whereby the ends are secured between the 15 spring 104 and its associated jaw 105. The whole yoke then moves forwardly and a pusher block 108 associated with the jaw 105 to which the spring 104 is secured, pushes the knot forward on the warp in position with the knots previously formed. The block 108 depends from its associated jaw 105 by a 20 depending supporting arm 109. The spreader 103 is supported by an upwardly extending arm 110 to be in alinement with the upper 25 ends of the needles when the needles are in their upward position. For controlling the pivotal movement of the jaws, a depending finger 112 carried by a supporting block 113 on one of the jaws, is arranged to move over a cam surface 114 supported by the upper 30 movable frame. The jaws are horizontally pivoted to the forward extension 106 of the shaft 96, as at 115, whereby, as shown in Fig. 7, they may ride up upon the knots previously 35 formed to disengage the end of the new knot from the jaws before the new cycle of the needles or pusher and spreader assembly has moved rearwardly to the position shown in Fig. 2 by the cam 101.

For cutting the threads on the bobbin disks between the fingers 45, a scissors device is provided, as shown in Fig. 1, the scissors including a fixed jaw and a movable jaw. The movable jaw is provided with an operating extension 125, the rear end of which is received within an eccentric groove of a drive wheel 116. The wheel 116 is driven by a chain 117 at the same speed as the cam 101 and acts to close the jaws of the scissors to cut the thread just after the bobbins have been turned by the gear 72. The arrangement is such that prior to the taking of a thread from any one of the bobbin disks by the needles, the thread in the next adjacent span is cut so that at all times the threads are cut for selection by the needles. In the original positioning of the device, the threads are all cut along the rear side of the bobbin at the place where the scissors are provided. Thus the bobbins are free to reciprocate past the scissors and after turning the scissors operate to cut the new thread of the bobbin which has been turned.

In the operation of the device, starting 60 from the zero position of the apparatus, it will be seen that the needles are in downward position. By operation of the motor 18, the shaft 29 is operated at twice the speed of the other shafts, all of which operate at the same speed. As the needle starts to move

up and before it has reached the warp threads 15, the cam 79 moves to turn the shafts 13 and 14, whereby the upper and lower structures 11 and 12 are moved a predetermined distance across the loom, thus arranging the 70 assembly whereby the needles will tie a knot on the warp threads next adjacent to those from which the knot has previously been tied. With the needles still moving up and before they have reached the proximity of the bobbins, the cam 61 is moved to lower the pusher bar 59, thus permitting the registration of one of the fingers 56 of one of the levers 55, so that if the predetermined arrangement of 75 apertures of the plate 57 permits, one of the levers will be dropped, thus locking the jaws 49 thereof about the registering recess in the sleeve 44. This position of parts being shown in Fig. 2. The cam 66 then operates 80 to permit forward movement of the upper end of the lever 47, whereby the bobbins and bobbin carriage will be moved rearwardly under the influence of the spring 68, until the rear end of the bobbin assembly strikes 85 the jaws which have been locked about the 90 sleeve 44.

The next step in the operation, which also occurs prior to the movement of the needles to engagement with the threads, is the rotation of the bobbin-rotating shaft 69, which is 95 controlled by rotation of the shaft 74 and actuation of the bobbin shaft 69 through the interengagement of the fingers 73 with the fingers 77.

After the completion of these movements, 100 all of which are completed prior to the first half of the first revolution of the needle-operating shaft 29, the needle continues its upward movement and the lower portion thereof moves backwardly in the guideway 36, thus tilting forwardly the front end of the needles, whereby they follow the upward arcuate forwardly-moving path. At the upper end of such path the cam 101 operates to 105 permit forward movement of the spreader and jaw assembly, whereby the spreader 103 is received between the needles, forcing them apart, whereby they pass through the threads as indicated in Figs. 23, 24 and 25, the movement being indicated in Figs. 25 and 26. The 110 needles then continue their downward movement, as indicated in Figs. 27 and 28, and again, without further movement of the other cams of the device, pass upwardly, the wheel 34 being rotated, as indicated in Fig. 19, to bring the upper ends of the needles together as they pass up this time between the threads on either side of which they had first passed.

The completed upward movement in conjunction with the holding of the upper ends of the threads by the spring fingers 104, as hereinbefore described, releases the needles and they lower to the original zero position. During such lowering, the cam 101 115 120 125 130

operates to permit complete forward movement of the pusher assembly under the influence of the spring 97, whereby the knot formed, as indicated in Fig. 30, is pushed 5 forwardly to abutting relation with the prior formed knots. The jaws are then retracted by the enlarged portion of the cam 101 and the whole machine is again in the zero setting. At the expiration of one complete 10 transverse travel of the structures over the device, the lever 88 may be moved to disengage the threaded nuts from the threaded shafts and the structures may be manually returned to the original position. At the 15 same time, the warp is moved as by the structure indicated in detail in Fig. 20, the beams 16 and 17 being provided with ratchet wheels 118 and 119, respectively, which may be engaged by dogs 120 carried on elongated arms 21, the link 122 thereof being adapted for actuation manually by a handle 123. Obviously, automatic means in the form of a cam, may be provided for moving the beams 20 and for resetting the structures on the initial side of the machine. 25

The forming of the knots in the form and by the operation indicated in Figs. 23 to 32, inclusive, is only one form of knot which may be tied by the present invention. The 30 so-called Chinese knot may be readily formed by the device as indicated in Figs. 33 to 36, inclusive. In the formation of this type of knot a mere variation in the configuration of the spreader and needle operating cams is required.

From the foregoing it will readily be seen that the invention provides a novel and improved knot-forming loom, and for automatic operation of the device in accordance with a preconceived design, the selection of colored threads from the various bobbins being in response to the preformed apertured plate 57. 55

It will be understood that the invention is not confined to a device utilizing single bobbin and single needle assemblies. A plurality of such assemblies may be used, so that in a single operation of the machine a plurality of knots may be formed at one time. 60

It will be further understood that the invention is not confined to the specific structural details set forth, but that numerous changes, modifications and the full use of equivalents may be resorted to without departing from the spirit or scope of the invention as outlined in the appended claims. 65

What is claimed is:

1. In a loom, the combination with a stationary structure, of a needle assembly movable with respect thereto, said assembly including a plurality of needles pivotally movable with respect to each other, said assembly further including means for vertically reciprocating said needles, an inclined guide coacting with one end of the needle to forwardly

tilt said needles during the upper end of the vertical movement to provide a forward arcuate path at the upper extremity of their cycle. 70

2. In a loom, the combination with a stationary structure, of a needle assembly movable with respect thereto, said assembly including a plurality of needles pivotally movable with respect to each other, said assembly further including means for vertically reciprocating said needles, a rock shaft on which said needles are mounted for pivotal movement, a straight guide for said rock shaft, and an inclined guide cooperating with said straight guide and one end of said needles to rock said shaft and upwardly tilt said needles during the upper and straight vertical movement to provide a forward arcuate path at the upper extremity of their cycle. 75

80 3. In a loom, the combination with a stationary structure, of a needle assembly movable with respect thereto, said assembly including a plurality of needles pivotally movable with respect to each other, said assembly further including means for vertically reciprocating said needles, said means including a vertically reciprocating needle shaft to which said needles are pivotally attached, and a shaft movable therewith in a path diverging from the path of said needle shaft, said second-mentioned shaft being associated with said needles to provide rocking movement thereof during the reciprocation. 85

90 4. In a loom, the combination with a stationary structure, of a needle assembly movable with respect thereto, said assembly including a plurality of needles pivotally movable with respect to each other, said assembly further including means for vertically reciprocating said needles, said means including a vertically reciprocating needle shaft to which said needles are pivotally attached, and a shaft movable therewith in a path diverging from the path of said needle shaft, said second-mentioned shaft being associated with 95 said needles to provide rocking movement thereof during the reciprocation, said second-mentioned shaft including a cam wheel positioned between said needles to pivotally move said needles with respect to each other. 100

105 5. In a loom, the combination with a stationary structure, of a needle assembly movable with respect thereto, said assembly including a plurality of needles pivotally movable with respect to each other, said assembly further including means for vertically reciprocating said needles, said means including a vertically reciprocating needle shaft to which said needles are pivotally attached, and a shaft movable therewith in a path diverging from the path of said needle shaft, said second-mentioned shaft being associated with said needles to provide rocking movement 110 thereof during the reciprocation, said second-mentioned shaft including a cam wheel 115 positioned between said needles to pivotally move said needles with respect to each other. 120

positioned between said needles to pivotally move said needles with respect to each other, together with means for automatically rotating said shaft and wheel.

6. In a loom, the combination with a stationary structure, of a bobbin assembly movable with respect thereto, said assembly including a plurality of longitudinally movable bobbins of disk configuration, said bobbins being independently rotatable.

10 7. In a loom, the combination with a stationary structure, of a bobbin assembly movable with respect thereto, said assembly including a plurality of longitudinally movable bobbins of disk configuration, said bobbins being independently rotatable, and means for selectively rotating one of said bobbins.

20 8. In a loom, the combination with a stationary structure, of a bobbin assembly movable with respect thereto, said assembly including a plurality of longitudinally movable bobbins of disk configuration, said bobbins being independently rotatable, and means for longitudinally moving said bobbins a predetermined distance.

30 9. In a loom, the combination with a stationary structure, of a bobbin assembly movable with respect thereto, said assembly including a plurality of longitudinally movable bobbins, said bobbins being independently rotatable, means for longitudinally moving said bobbins a predetermined distance, and means for selectively rotating one of said bobbins, the means for selection comprising the means for longitudinally moving said bobbins.

40 10. In a loom, the combination with a stationary structure, of a bobbin assembly movable with respect thereto, said assembly including a plurality of longitudinally movable bobbins of disk configuration, said bobbins being independently rotatable, means for longitudinally moving said bobbins a predetermined distance, and means for selectively rotating one of said bobbins, the means of selection comprising the means for longitudinally moving said bobbins.

45 11. In a loom, the combination with a stationary structure, of a bobbin assembly movable with respect thereto, said assembly including a plurality of longitudinally movable bobbins, said bobbins being independently rotatable, means for longitudinally moving said bobbins a predetermined distance, and means for selectively rotating one of said bobbins, the means of selection comprising the means for longitudinally moving said bobbins, said means for longitudinally

55 moving said bobbins a predetermined distance, and means for selectively rotating one of said bobbins, the means of selection comprising the means for longitudinally moving said bobbins, said means for longitudinally moving and selecting being automatically operated with the operation of the loom.

60 12. In a loom, the combination with a stationary structure, of a bobbin assembly movable with respect thereto, said assembly including a plurality of longitudinally mov-

able bobbins, said bobbins being independently rotatable, means for longitudinally moving said bobbins a predetermined distance, and means for selectively rotating one of said bobbins, the means of selection comprising the means for longitudinally moving said bobbins, said means for longitudinally moving and selecting being automatically operated with the operation of the loom, said means for rotating being similarly operated after operation of said selecting means.

70 13. In a loom, the combination with a stationary structure, of a movable bobbin assembly including a plurality of associated bobbin disks, each of said disks comprising a control body, and a plurality of pairs of thread-holding fingers radiating therefrom.

75 14. In a loom, the combination with a stationary structure, of a movable bobbin assembly including a plurality of associated bobbin disks, said disks having a common supporting sleeve and means for simultaneously moving all of said bobbins longitudinally of said sleeve.

80 15. In a loom, the combination with a stationary structure, of a movable bobbin assembly including a plurality of associated bobbin disks, said disks having a common supporting sleeve and means for simultaneously moving all of said bobbins longitudinally of said sleeve, said means including a cam-controlled lever arm.

85 16. In a loom, the combination with a stationary structure, of a movable bobbin assembly including a plurality of associated bobbin disks, said disks having a common supporting sleeve, and means for simultaneously moving all of said bobbins longitudinally of said sleeve, said means including a cam-controlled lever arm, and control means 100 for controlling the movement of said bobbins by said arm.

90 17. In a loom, the combination with a stationary structure, of a movable bobbin assembly including a plurality of associated bobbin disks, said disks having a common supporting sleeve, and means for simultaneously moving all of said bobbins longitudinally of said sleeve, said means including a cam-controlled lever arm, and control means 110 for controlling the movement of said bobbins by said arm, said control means including a preformed pattern and arms selectively controlled thereby to engage said sleeve to limit movement of said bobbins thereover.

115 18. In a loom, the combination with a stationary structure, of a movable bobbin assembly including a plurality of associated bobbin disks, said disks having a common supporting sleeve, and means for simultaneously moving all of said bobbins longitudinally of said sleeve, said means including a cam-controlled lever arm, and control means 125 for controlling the movement of said bobbins by said arm, said control means including a 130

- prefomed pattern and arms selectively controlled thereby to engage said sleeve to limit movement of said bobbins thereover, said sleeve including recesses and jaws carried by said arms operable by movement thereof to be received in said recesses.
19. In a loom, the combination with a stationary structure, of a movable bobbin assembly including a plurality of associated bobbin disks, said disks having a common supporting sleeve, means for simultaneously moving all of said bobbins longitudinally, and means for selectively rotating one of said bobbins.
- 15 20. In a loom, the combination with a stationary structure, of a movable bobbin assembly including a plurality of associated bobbin disks, said disks having a common supporting sleeve, means for simultaneously moving all of said bobbins longitudinally, and means for selectively rotating one of said bobbins, said rotating means comprising a longitudinally stationary disk-engaging member within said sleeve operable to rotate 20 the bobbin disk which is longitudinally moved for engagement therewith.
- 20 21. In a loom, the combination with a stationary structure, of a movable bobbin assembly including a plurality of associated bobbin disks, said disks having a common supporting sleeve, means for simultaneously moving all of said bobbins longitudinally, and means for selectively rotating one of said bobbins, said rotating means comprising a longitudinally stationary disk-engaging member within said sleeve operable to rotate the bobbin disk which is longitudinally moved for engagement therewith, said disks and rotating means having interengaging angular faces to permit respective longitudinal movement and simultaneous rotating movement.
- 30 35 40 45 50 55 60 65 70 75 80 85 90 95 100 105 110 115 120 125 130
22. In a loom assembly, the combination with a stationary structure and movable needle and bobbin assemblies, of a longitudinally movable needle-spreading and thread-engaging assembly, said last-mentioned assembly including a needle spreader movable to spread the upper ends of a pair of needles upon their upward movement.
23. In a loom assembly, the combination with a stationary structure and movable needle and bobbin assemblies, of a longitudinally movable needle-spreading and thread-engaging assembly, said last-mentioned assembly including thread-engaging jaws operable to tie a knot formed by said needle assembly forwardly of said loom.
24. In a loom assembly, the combination with a stationary structure and transversely movable needle and bobbin assemblies, of a transversely and longitudinally movable needle-spreading and thread-engaging assembly, said last-mentioned assembly including a needle assembly and

a needle assembly and thread-engaging jaws simultaneously movable.

25. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously movable.

26. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously movable, one of said jaws having a cam member for controlling movement of said jaws by longitudinal movement of said assembly.

27. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously movable, one of said jaws having a cam member for controlling movement of said jaws by longitudinal movement of said assembly, and a needle spreader carried by said structure.

28. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously movable, one of said jaws having a cam member for controlling movement of said jaws by longitudinal movement of said assembly, and a needle spreader carried by said structure in a plane above said jaws.

29. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously movable, one of said jaws having a cam member for controlling movement of said jaws by longitudinal movement of said assembly, a needle spreader carried by said structure in a plane above said jaws, and means for co-ordinately moving said assemblies with movement of said needle and bobbin assemblies.

30. In a loom assembly, the combination with a stationary structure and movable needle and bobbin assemblies, of a longitudinally movable needle-spreading and thread-engaging assembly, said last-mentioned assembly including a needle assembly and thread-engaging jaws simultaneously mov-

- able, one of said jaws having a cam member for controlling movement of said jaws by longitudinal movement of said assembly, a needle spreader carried by said structure in a plane above said jaws, and means for co-ordinately moving said assemblies with movement of said needle and bobbin assemblies, said moving means including a cam-controlled lever arm.
- 10 31. In a loom assembly, the combination of a stationary work-carrying frame, a bobbin assembly and a needle assembly, said needle assembly including a pair of pivoted needles, and means for imparting vertical reciprocation to said needles, said means being operable to give the upper ends of said needles a forward arcuate path and to pivotally move said needles with respect to each other during their reciprocation.
- 15 32. In a loom assembly, the combination of a stationary work-carrying frame, a bobbin assembly and a needle assembly, said needle assembly including a pair of pivoted needles, means for imparting vertical reciprocation to said needles, said means being operable to give the upper ends of said needles a forward arcuate path and to pivotally move said needles with respect to each other during their reciprocation, and independent means co-operatively movable to give pivotal movement to said needles during their reciprocation.
- 20 33. In a loom assembly, the combination of a stationary work-carrying frame, a bobbin assembly and a needle assembly, including a pair of pivoted needles, said bobbin assembly including a plurality of bobbins for selective position for co-operation with said needles.
- 25 34. In a loom assembly, the combination of a stationary work-carrying frame, a bobbin assembly and a needle assembly, including a pair of pivoted needles, said bobbin assembly including a plurality of bobbins for selective position for co-operation with said needles, said bobbins being simultaneously longitudinally movable and selectively rotatable.
- 30 35. In a loom assembly, the combination of a stationary work-carrying frame, a bobbin assembly and a needle assembly, including a pair of pivoted needles, said bobbin assembly including a plurality of bobbins for selective position for co-operation with said needles.
- 35 36. In a loom assembly, the combination of a stationary work-carrying frame, a bobbin assembly and a needle assembly, including a pair of pivoted needles, said bobbin assembly including a plurality of bobbins for selective position for co-operation with said needles, said bobbins being simultaneously longitudinally movable and selectively rotatable, and predetermined means for controlling the movement of said bobbins.
- 40 37. In a loom assembly, the combination of a stationary work-carrying frame, a bobbin assembly and a needle assembly, including a pair of pivoted needles, said bobbin assembly including a plurality of bobbins for selective position for co-operation with said needles, said bobbins being simultaneously longitudinally movable and selectively rotatable, and predetermined means for controlling the movement of said bobbins, said means being operable to select the bobbin to be rotated.
- 45 38. A loom including a stationary work-carrying frame, and simultaneously transversely-movable bobbin and needle assemblies, said bobbin assembly including a plurality of bobbins longitudinally movable with respect to said needle assembly to selectively co-operate therewith.
- 50 39. A loom, including a stationary work-carrying frame, simultaneously transversely-movable bobbin and needle assemblies, said bobbin assembly including a plurality of bobbins longitudinally movable with respect to said needle assembly to selectively co-operate therewith, and interconnected means for transversely moving said bobbins after said transverse movement.
- 55 40. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, and a selective bobbin-rotating means operable by said interconnected means after longitudinal movement of said bobbins.
- 60 41. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, and a selective bobbin-rotating means operable by said interconnected means after longitudinal movement of said bobbins, said interconnected means being operable to reciprocate said needle assembly, whereby said assembly will be given two cycles of reciprocation with each cycle

of said assembly-moving, bobbin-moving and rotating means.

42. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, and means transversely movable with said bobbin assembly for controlling the selective longitudinal movement and rotation thereof.

43. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, and a stationary pattern plate for engagement with said last-mentioned means for effecting control thereby.

44. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, and a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, said needle assembly including a pair of needles and means for giving the needles a forward arcuate path at the upper end of both their cycles.

45. A loom, including a stationary work-

carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, and a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, said needle assembly including a pair of needles and means for giving the needles a forward arcuate path at the upper end of both their cycles and for pivotally moving the upper ends of said needles together during the second cycle of the reciprocation.

46. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, said needle assembly including a pair of needles, means for giving the needles a forward arcuate path at the upper end of both their cycles and for pivotally moving the upper ends of said needles together during the second cycle of the reciprocation, and independent means for spreading the upper ends of said needles during their first cycle.

47. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and

and rotating means, said needle assembly including a pair of needles, means for giving the needles a forward arcuate path at the upper end of both their cycles and for pivotally moving the upper ends of said needles together during the second cycle of the reciprocation, and independent means for spreading the upper ends of said needles during their first cycle, said independent means including a thread-engaging jaw for moving a knot formed by said needles.

48. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins said interconnected means being operable to reciprocate said needle assembly, whereby said assembly will be given two cycles of reciprocation with each cycle of said assembly-moving, bobbin-moving and rotating means, said needle assembly including a pair of needles, means for giving the needles a forward arcuate path at the upper end of both their cycles and for pivotally moving the upper ends of said needles together during the second cycle of the reciprocation, and independent means for spreading the upper ends of said needles during their first cycle, said independent means including a thread-engaging jaw for moving a knot formed by said needles, said interconnected means being operable to move said independent means at the end of the second cycle of said needles.

49. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, a stationary pattern plate for engagement with said last-mentioned means for effecting control thereby, said needle assembly including a pair of needles, and means for giving the needles a forward arcuate path at the upper end of both their cycles, and for

pivotally moving the upper ends of said needles together during the second cycle of the reciprocation.

50. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, a stationary pattern plate for engagement with said last-mentioned means for effecting control thereby, said needle assembly including a pair of needles and means for giving the needles a forward arcuate path at the upper end of both their cycles and for pivotally moving the upper ends of said needles together during the second cycle of the reciprocation, and independent means for spreading the upper ends of said needles during their first cycle, said independent means including a thread-engaging jaw for moving a knot formed by said needles, said interconnected means being operable to move said independent means at the end of the second cycle of said needles.

51. A loom, including a stationary work-carrying frame, simultaneously transversely-movable bobbin and needle assemblies, said bobbin assembly including a plurality of bobbins longitudinally movable with respect to said needle assembly to selectively co-operate therewith, interconnected means for transversely moving said assemblies and for longitudinally moving said bobbins after said transverse movement, a selective bobbin-rotating means operable by said interconnected means after longitudinal movement of said bobbins, said interconnected means being operable to reciprocate said needle assembly, whereby said assembly will be given two cycles of reciprocation with each cycle of said assembly-moving, bobbin-moving and rotating means, a stationary pattern plate for engagement with said last-mentioned means for effecting control thereby, said needle assembly including a pair of needles and means for giving the needles a forward arcuate path at the upper ends of both their cycles and for pivotally moving the upper ends of said needles together during the second cycle of the reciprocation, independent means for spreading the upper ends of said needles during their first cycle, said independent means including a thread-engaging jaw for

moving a knot formed by said needles, said interconnected means being operable to move said independent means at the end of the second cycle of said needles, and scissors for cutting the thread of the selectively rotated bobbin, operable by said interconnected means after selective rotation of said bobbin.

Signed at New York in the county of New York and State of New York this 16th day of May, A. D. 1930.

HARRY M. PATERNAYAN.
